UNITED STATES PATENT OFFICE.

ALBERT W. MORSE, OF NEW YORK, N. Y., ASSIGNOR TO THE NATHAN MANUFACTURING COMPANY, OF NEW YORK, N. Y., A CORPORATION OF NEW YORK.

WATER-GAGE.

1,234,924.

Specification of Letters Patent. Patented July 31, 1917.

Application filed May 31, 1913. Serial No. 770,884.

To all whom it may concern:

Be it known that I, ALBERT W. MORSE, a citizen of the United States, residing at New York, in the county of New York and State 5 of New York, have invented certain new and useful Improvements in Water-Gages, of which the following is a specification.

This invention relates to water gages, and its novelty consists in the construction and 10 adaptation of the parts as will be more fully hereinafter pointed out.

Gages of this character, especially where they are to be used on locomotives and adapted to measure the height of bodies of 15 very hot water, are apt to have their sight glasses shattered under the influence of the unequal temperatures on their opposite surfaces and are especially apt to leak because of the unequal expansion and contraction 20 of the contacting parts. They should, therefore, be most carefully packed, and the purpose of this invention is to provide a device of this character, simple in form, readily packed and easily maintained in an efficient condition.

In the drawings, Figure 1 is a transverse horizontal section of a device embodying the invention, and Fig. 2 is a miniature front elevation thereof; Fig. 3 is a transverse section of a different form of the device, and 30 Fig. 4 is a miniature front elevation thereof. Fig. 5 is a transverse section of a yet different form of the device, and Fig. 6 is a miniature front elevation thereof.

The device comprises first of all a casing having two side walls 20, one on each lateral edge of a centrally placed sight glass 30 which is provided with the usual rear flutings or recesses indicated at 31. Each wall 40 20 of the casing has at its front end an inwardly turned flange 21 and between the two flanges is a longitudinal sight opening indicated at 32. The sight glass is smaller in breadth than the space between the walls 45 of the casing, and it does not extend to the rear wall of the latter so that there is left back of this glass a space 33 adapted to receive the column of water, the height of which is to be measured.

At the rear of the casing is a longitudinal fin or extension 22 which is suitably threaded 50 at intervals to receive set screws indicated at 40 and which fin is expanded at 23 and internally threaded to receive a tubular 55 nut 41 adapted to fit over the set screw 40

(Figs. 1 and 3). This nut bears against packing 41^a and compresses it tightly against the set screw 40.

Between the front side of the glass 30 and each flange 21 there is arranged a suitable packing 50 and back of this and on each edge of the glass is arranged another packing 51, and back of each piece of the latter packing there is arranged a plate 52 and interposed between these plates and the set 65 screw 40 is a compression member 42.

It will be understood, of course, that the casing at its top and bottom is provided with fittings 60 by means of which it is connected to the reservoir or receptacle containing the 70 water to be measured, and that there are provided drainage cocks and the usual adjuncts common to the art.

In Figs. 3 and 4 there is illustrated a form of the device in which the sight glass 75 is substantially square in section and in which the side walls of the casing are arranged parallel to each other instead of being at an acute angle. The compression member 42 is also substantially in the form 80 of a flat bar, and the plates 52 instead of being straight, are L-shaped. The principle of the invention, therefore, is the same as before.

In Figs. 5 and 6 there is illustrated a further modified form in which there is shown a sight glass comprising a plurality of elements between which there are arranged flanges 210 which overlap the element on each side. The packings 51 in this modification are not only placed between the two outer sight glass elements and the walls 20, but are also placed between such elements and the central sight glass element. The lock nut 41 is also placed outside of the 90 extension 43 instead of inside. There is, however, no departure from the principle of the invention in this modification, and it simply serves to illustrate the application of the invention to varying circumstances. In 100 this form, it will be noted that the inner end of the set screw 40 is tapered and operates between the plates to force them apart.

It will be noticed that in the forms of the device illustrated in Figs. 1 and 5 that the sight glasses are in the form of a truncated sector (disregarding the flutings 31). This form serves an important purpose in securing the result that the glass on account of its front curved surface uniformly increases 110

in thickness from each edge toward the middle and consequently it is thickest at the middle where it is not supported or reinforced as it is at the edges.

5. What I claim is:

1. A water gage comprising a sight glass, a casing adapted partially to surround the same and having a wall on each edge of the sight glass, and rearwardly extending beyond the same, each wall having in front an inturned flange, a packing interposed between the glass and each wall and means bearing against the packing at the rear to compress it against such inturned flange.

15 2. A water gage comprising a sight glass, a casing adapted partially to surround the same and having a wall on each edge of the sight glass, and rearwardly extending beyond the same, each wall having in front an inturned flange, a packing interposed between the glass and each wall and means for bringing pressure to bear upon the packing from the rear to compress it against such in-turned flange including separable plates, one arranged between the sight glass and each wall of the casing.

29

25

3. A water gage comprising a sight glass, a casing adapted partially to surround the same and having a wall on each edge of the 30 sight glass, and rearwardly extending beyond the same, each wall having in front an inturned flange, a packing interposed between the glass and each wall and means for bringing pressure to bear upon the 35 packing from the rear to compress it against such inturned flange including separable plates, one arranged between the sight glass and each wall of the casing, and compression means adapted to be moved toward 40 said plates.

4. A water gage comprising a sight glass, a casing adapted partially to surround the same and having a wall on each edge of the sight glass, and rearwardly extending beyond the same, each wall having in front an inturned flange, a packing interposed between the glass and each wall and means for bringing pressure to bear upon the packing from the rear to compress it against such in-turned flange including separable plates, one arranged between the sight glass and each wall of the casing, and compression means adapted to be moved toward said plates and means for holding said means in position after adjustment.

5. A water gage comprising a sight glass, a casing adapted partially to surround the same and having a wall on each edge of the sight glass, and rearwardly extending beyond the same, each wall having in front an inturned flange, a packing interposed between the glass and each wall and means for bringing pressure to bear upon the packing from the rear to compress it against such inturned flange including separable

plates, one arranged between the sight glass and each wall of the casing, and compression means adapted to be moved toward said plates and means for holding said means in position after adjustment consisting of a threaded bolt inserted in the rear of the casing. 70

6. A water gage comprising a sight glass, a casing adapted partially to surround the same and having a wall on each edge of the sight glass, and rearwardly extending beyond the same, each wall having in front an inturned flange, a packing interposed between the glass and each wall and means bearing against the rear side of each packing for simultaneously bringing pressure to bear upon the same from the rear. 75 80

7. A water gage comprising a sight glass, a casing adapted partially to surround the same and having a wall on each edge of the sight glass, and rearwardly extending beyond the same, each wall having in front an inturned flange, a packing interposed between the glass and each wall and means for simultaneously bringing pressure to bear upon each packing from the rear including two separable plates, each in the rear of the packing.

8. A water gage comprising a sight glass, a casing adapted partially to surround the same and having a wall on each edge of the sight glass, and rearwardly extending beyond the same, each wall having in front an inturned flange, a packing interposed between the glass and each wall and means for simultaneously bringing pressure to bear upon each packing from the rear including two separable plates, each in the rear of the packing, and a device adapted when pressed to contact with the rear edges of both plates. 95 100

9. A water gage comprising a sight glass, a casing adapted partially to surround the same and having a wall on each edge of the sight glass, and rearwardly extending beyond the same, each wall having in front an inturned flange, a packing interposed between the glass and each wall and means for simultaneously bringing pressure to bear upon each packing from the rear including two separable plates, each in the rear of the packing, and a device adapted when pressed to contact with the rear edges of both plates, and means for moving the device forward.

10. A water gage comprising a sight glass, a casing adapted partially to surround the same and having a wall on each edge of the sight glass, and rearwardly extending beyond the same, each wall having in front an inturned flange, a packing interposed between the glass and each wall and means for simultaneously bringing pressure to bear upon each packing from the rear including two separable plates, each in the rear of the packing, and a device adapted when pressed to contact with the rear edges of 130

both plates, and means for moving the device forward, consisting of a movable member threaded into the rear wall of the casing.

11. A water gage comprising a sight glass, 5 a casing adapted partially to surround the same and having a wall on each edge of the sight glass, and rearwardly extending beyond the same, each wall having in front an inturned flange, a packing interposed between the glass and each wall and means for simultaneously bringing pressure to bear upon each packing from the rear including two separable plates, each in the rear of the packing, and a device adapted when 15 pressed to contact with the rear edges of both plates, and means for moving the device forward, and further means for holding it to any position.

12. A water gage comprising a sight glass, 20 a casing adapted partially to surround the same and having a wall on each edge of the sight glass, and rearwardly extending beyond the same, each wall having in front an inturned flange, a packing interposed between the glass and each wall and means for simultaneously bringing pressure to bear upon each packing from the rear including two separable plates, each in the rear of the packing, and a device adapted when pressed 25 to contact with the rear edges of both plates, and means for moving the device forward, and further means for holding it to any position consisting of a lock nut.

13. In a device of the character described, 35 a sight glass, a casing adapted to surround the same at the rear and edges and provided with walls and integral inturned flanges affording a sight opening between their edges, a packing adapted to be interposed between the glass and walls and contacting with the inturned flange, a plate at the rear of each packing, and means moved from the rear to force each plate toward its packing and to hold it thereafter in position.

45 14. In a device of the character described, a sight glass, a casing adapted to extend in rear of the same and provided with walls and integral inturned flanges affording a sight opening between their edges, packing means adapted to be interposed between the glass and walls and contacting with the flange, plates at the rear of the packing means, and means moved from the rear to force each plate toward said packing means 55 and to hold it thereafter in position, including a tapered member operating on both plates, a set screw moved from the rear of the casing and a lock nut on the screw.

15. A water gage, comprising a casing, a 60 plurality of sight glass elements arranged therein, flanges forming a part of the casing and adapted to overlap the sides of the sight glass elements, packings adjacent to each edge of the sight glass elements at their front and behind the overlapping flanges

and adapted to contact with said flanges, and means for simultaneously compressing all of the packings against the flanges.

16. A water gage comprising a casing, a plurality of sight glass elements arranged 70 therein, substantially edge to edge, flanges forming a part of the casing and adapted to overlap the sides of the sight glass elements, packings adjacent to each edge of the sight glass elements at their front ends and being located between the glass elements and behind the flanges, and means for simultaneously compressing all of the packings, consisting of a plate back of each packing and means including a tapered member adapted 75 to coöperate with the rear edges of all of the plates.

17. A water gage comprising a casing, a plurality of sight glass elements arranged 80 therein substantially edge to edge, flanges forming a part of the casing and adapted to overlap the adjacent sides of the sight glass elements, packings adjacent to each edge of the sight glass elements at their front ends and between the same and adapted 85 to contact with the flanges, and means for simultaneously compressing all of the packings, consisting of a plate back of each packing and means including a tapered member adapted to coöperate with the rear edges of 90 all of the plates and a set screw threaded into the casing to move the tapered member.

18. A gage of the character set forth, comprising a casing having spaced walls, a sight glass located in the casing between 100 the walls and spaced therefrom, packing located in each of said spaces and interposed between each edge of the glass and the adjacent wall, compressing plates, one of which enters each of the said spaces and 105 bears against the rear side of the corresponding packing to compress said packing in one direction and thereby expand it laterally against the edge of the glass and the wall, and means bearing against the plates 110 to force the same forward.

19. A gage of the character set forth, comprising a casing having spaced walls, a sight glass located in the casing between the walls and spaced therefrom, packing 115 located in each of said spaces and interposed between each edge of the sight glass and the adjacent wall, compressing plates one of which enters each of the said spaces on opposite sides of the glass and bears 120 against the rear side of the corresponding packing, and means bearing against both plates and including a common element for forcing them forward.

20. A gage of the character set forth, comprising a casing having a plurality of sight 125 openings located side by side and a flange separating each two adjacent spaces, a plurality of sight glass elements in the casing arranged edge to edge and having their op- 130

posite edges spaced apart and located behind the flange, packing interposed between said edges and behind said flange, and means bearing against the packing between the 5 elements for compressing the said packing against the flange and expanding it laterally against the opposite edges of the elements.

21. In a gage of the character set forth, a glass comprising separate elements disposed 10 substantially edge to edge and having front

curved faces located on substantially the arc of a common circle and having fluted rear faces arranged in angular relation to each other.

In testimony whereof I affix my signature 15 in presence of two witnesses,

ALBERT W. MORSE.
